CLAIM

The ornamental design for an automobile mechanic's creeper, as shown and described.

DESCRIPTION

FIG. 1 is a top plan view of an automobile mechanic's creeper showing our new design;

FIG. 2 is a bottom plan view thereof;

FIG. 3 is a right side elevational view thereof, the left side elevational view being a mirror image of that shown;

FIG. 4 is a rear elevational view thereof;

FIG. 5 is a front elevational view thereof; and,

FIG. 6 is a top and front perspective view thereof.
